UNITED STATES PATENT OFFICE

ALFRED W. BRUCE, OF NEW YORK, N. Y.

LOCOMOTIVE

Application filed February 6, 1930. Serial No. 426,232.

This invention relates to locomotives, and more particularly to an improved construction of main frame, cylinder saddle, cylinder castings, and bumper beam extension.

5 An object of the invention is to provide a construction wherein the main frame terminates at the rear of the cylinder saddle, and the saddle is extended laterally beyond the main frame to provide increased space for the accommodation of steam passageways, and in the case of three cylinder locomotives, increased space for the accommodation of a middle cylinder, a distribution valve chest therefor, and steam passageways.

15 The improvement claimed is hereinafter fully set forth.

In the accompanying drawings: Figure 1 is a view of a locomotive structure embodying the invention, one-half in top plan, and one-half in horizontal section taken on the line I—I of Fig. 3; Fig. 2, a longitudinal vertical section taken on the line II—II of Fig. 1; Fig. 3, a view of the construction shown in Fig. 1, one-half in front elevation, and one half in transverse vertical section taken on the line III—III of Fig. 1; Fig. 4, a transverse horizontal section showing the cylinder saddle of Fig. 1 modified to provide vertical bolting flanges for attaching the cylinder castings; Fig. 5, a top plan view of a modified form of construction embodying a middle cylinder and its valve chest, part of the construction being shown in broken section on the line V—V of Fig. 7; Fig. 6, a side view in elevation of the construction shown in Figure 5; and, Fig. 7, an enlarged view of the construction shown in Fig. 5, one-half in front elevation and one-half in transverse vertical section taken on the line VII—VII of Fig. 6.

In the practice of the invention, referring descriptively to the specific embodiment thereof which is herein exemplified, the locomotive bed comprises a main frame A, a cylinder saddle B, a bumper beam extension C, and a pair of cylinder castings D.

The main frame A comprises a pair of main side frame members 11, having pedestal jaws 12, and cross-tied together by a horizontal

transverse top web 13 and vertical transverse webs 14.

The cylinder saddle B comprises front and rear vertical transverse end walls respectively numbered 15 and 16; vertical longitudinal side walls 17 each joined to the end walls and formed with bolt holes 18 for the application of a cylinder casting; exhaust steam passageways 20; a smoke box fit 21; an an exhaust nozzle seat 22.

55 Each cylinder casting D comprises a cylinder 23; a distribution valve chest 24; exhaust steam passageways 25, communicating with one of the steam passageways 20, of the saddle; and bolting flanges 26, for attachment to the saddle. The front end of the main frame A of the bed terminates at the rear end wall 16, of the saddle B, to which wall it is joined inwardly of the ends thereof, so that the side walls 17 of the saddle are disposed laterally beyond the side frame members 11. This form of construction provides ample space in the saddle for the accommodation of steam pipes, and to enable the bolts 27, for attaching the cylinder casting, to be conveniently applied.

65 The bumper beam extension C comprises two longitudinal vertical walls 28; a horizontal web 29 joined to the tops of the longitudinal walls 28; a horizontal web 30 joined to the bottoms of the longitudinal walls; and a transverse vertical wall 31 joined to the front ends of the webs and vertical walls and adapted for the application of a bumper beam. If desired the bumper beam may be made integral with the extension. The rear end of the bumper beam extension is joined to the front end wall 15 of the cylinder saddle, its longitudinal vertical walls 28 being disposed inwardly of the ends of the saddle wall 15.

75 The main frame A, the cylinder saddle B, and the bumper beam extension C, are preferably formed together as an integral casting, but it is within the contemplation of the invention to form them separately and then to secure the front end of the main frame to the rear of the cylinder saddle, and the bumper beam extension to the front of the cylinder saddle.

In Figure 4 of the drawings is shown a modification wherein the side walls 17 of the cylinder saddle are extended beyond the front and rear end walls 15 and 16, to provide 5 flanges 17a for the attachment of bolts 27 which pass through the flanges 26 of the cylinder saddle castings.

In Figures 5, 6, and 7, is shown another modification wherein the cylinder saddle is 10 formed with a middle cylinder 32; a distribution valve chest 33 for such cylinder; a steam delivery passageway 34, leading to such valve chest; an exhaust passage 35; steam discharge passageways 36, leading 15 from each valve chest discharge passage of each outside cylinder casting to the exhaust passage 35; and two steam discharge passageways 37 each leading from the valve chest 33 to one of the steam discharge passageways 36.

The side frame members 38 of the main frame A are formed as separate castings each being bolted to one of the vertical longitudinal walls 39, which extend rearwardly from the rear wall 40, of the cylinder saddle and are disposed inwardly of the ends of such rear wall. The side walls 41 of the cylinder saddle converge toward one another from their tops down and each cylinder casting D 25 is formed with an attaching face inclined complementally to the opposed wall 41, of the saddle.

The bumper beam extension C has longitudinal vertical walls 42 which are joined to the front wall 43 of the cylinder saddle inwardly of the ends thereof.

In three cylinder locomotives where valve gears of the Gresley type are employed, that is, valve gears which operate the valve of the distribution valve chest for the middle cylinder by the resultant movement of the two component movements of the outside valves, it is desirable that the three valve 40 chests be substantially in horizontal alignment. The present invention by affording 45 greatly increased space in the saddle in the direction of the width thereof, enables the middle cylinder valve chest to be incorporated in the saddle in horizontal alignment with the valve chests of the outside cylinder castings.

While two of the preferred forms of construction have been shown, it is obvious that many variations in procedure, and in the 50 arrangement and construction of the parts can be made, and the invention is not therefore limited to the particular embodiments disclosed, but includes such changes and modifications as come within the spirit and scope 55 of the invention as set forth in the appended claims.

The invention claimed and desired to be secured by Letters Patent is:

1. In a locomotive, the combination of a 60 pair of parallel side frame members; a cyl-

inder saddle disposed immediately forward of the front ends of said side frame members, the said saddle having, on at least one side, a longitudinal upstanding face disposed laterally beyond the adjacent side frame member to provide increased lateral space within said saddle, and adapted for attachment of a cylinder casting; and a cylinder casting secured to said upstanding face. 70

2. In a locomotive, the combination of a 75 pair of parallel side frame members; a cylinder saddle disposed immediately forward of the front ends of said side frame members, the said saddle having, on its opposite sides, longitudinal upstanding faces disposed laterally beyond the adjacent side frame members to provide increased lateral space within 80 said saddle, and adapted for attachment of cylinder castings; and two cylinder castings, one attached to each upstanding face. 85

3. An integral casting for locomotives, comprising a pair of parallel side frame members; and a cylinder saddle disposed immediately forward of the front ends of said side frame members, the said saddle having, 90 on at least one side, a longitudinal upstanding face disposed laterally beyond the adjacent side frame member to provide increased lateral space within said saddle, and adapted for attachment of a cylinder casting. 95

4. An integral casting for locomotives, comprising a pair of parallel side frame members; a cylinder saddle disposed immediately forward of the front ends of said side frame members, the said saddle having, 100 on at least one side, a longitudinal upstanding face disposed laterally beyond the adjacent side frame member to provide increased lateral space within said saddle, and adapted for attachment of a cylinder casting; and a 105 crosstie member connecting the side frame members.

5. An integral casting for locomotives, comprising a pair of parallel side frame members; a cylinder saddle disposed immediately forward of the front ends of said side frame members, the said saddle having, 110 on its opposite sides, longitudinal upstanding faces disposed laterally beyond the adjacent side frame members to provide increased lateral space within said saddle, and adapted for attachment of cylinder castings; and a 115 crosstie member connecting the side frame members.

6. An integral casting for locomotives, 120 comprising a pair of parallel side frame members; a cylinder saddle disposed immediately forward of the front ends of said side frame members, the said saddle having, on its opposite sides, longitudinal upstanding 125 faces disposed laterally beyond the adjacent side frame members to provide increased lateral space within said saddle, and adapted for attachment of cylinder castings; a crosstie member connecting the side frame mem- 130

- bers; and a front frame member projecting forwardly of the cylinder saddle.
7. An integral casting for locomotives, comprising a pair of parallel side frame members; a cylinder saddle disposed immediately forward of the front ends of said side frame members, the said saddle having, on its opposite sides, longitudinal upstanding faces disposed laterally beyond the adjacent side frame members to provide increased lateral space within said saddle, and adapted for attachment of cylinder castings; a cross-tie member connecting the side frame members; and a front frame member extending forwardly of the cylinder saddle and having a support for a bumper beam.
8. In a locomotive, the combination of a pair of parallel side frame members; a cylinder saddle disposed immediately forward of the front ends of said side frame members, the said saddle having, on its opposite sides, longitudinal upstanding faces disposed laterally beyond the adjacent side frame members to provide increased lateral space within said saddle, said faces each being adapted for attachment of a cylinder casting; two cylinder castings, one attached to each of said faces; and a front frame member connected to, and terminating at the front of the saddle.
9. An integral casting for locomotives, comprising a pair of parallel side frame members; and a cylinder saddle disposed immediately forward of the front ends of said side frame members, said saddle having a middle cylinder and having, on at least one side, a longitudinal upstanding face disposed laterally beyond the adjacent side frame member to provide increased lateral space within said saddle, adapted for attachment of a side cylinder casting.
10. An integral casting for locomotives, comprising a pair of parallel side frame members; and a cylinder saddle disposed immediately forward of the front ends of said side frame members, said saddle having a middle cylinder, a valve chest for said cylinder, and on at least one side thereof a longitudinal upstanding face disposed laterally beyond the adjacent side frame member to provide increased lateral space within said saddle, and adapted for attachment of a side cylinder casting.
11. An integral casting for locomotives, comprising a pair of parallel side frame members; and a cylinder saddle disposed immediately forward of the front ends of said side frame members, said saddle having a middle cylinder, a valve chest for said cylinder, a steam exhaust passageway, a steam delivery passageway, and on at least one side thereof, a longitudinal upstanding face disposed laterally beyond the adjacent side frame member to provide increased lateral space within said saddle and adapted for attachment of a side cylinder casting.

12. An integral casting for locomotives, comprising a pair of parallel side frame members; and a cylinder saddle disposed immediately forward of the front ends of said side frame members, the said saddle having a middle cylinder, a valve chest for said cylinder, a steam exhaust passageway, a steam delivery passageway, a boiler fit, and, on at least one side thereof, a longitudinal upstanding face disposed laterally beyond the adjacent side frame member to provide increased lateral space within said saddle, said upstanding face being adapted for attachment of a side cylinder casting.

13. In a locomotive, the combination of two parallel side frame members; a cylinder saddle disposed immediately forward of the front ends of said side frame members, said saddle having a middle cylinder and, on at least one side thereof, a longitudinal upstanding face disposed laterally beyond the adjacent side frame member to provide increased lateral space within said saddle, said face being adapted for attachment of a side cylinder casting; and a cylinder casting secured to said upstanding face.

14. In a locomotive, the combination of two parallel side frame members; a cylinder saddle disposed immediately forward of the front ends of said side frame members, said saddle having a middle cylinder, a valve chest for said cylinder, and on at least one side thereof a longitudinal upstanding face disposed laterally beyond the adjacent side frame member to provide increased lateral space within said saddle, said face being adapted for attachment of a side cylinder casting; and a cylinder casting secured to said upstanding face.

15. In a locomotive, the combination of two parallel side frame members; a cylinder saddle disposed immediately forward of the front ends of said side frame members, said saddle having a middle cylinder, a valve chest for said cylinder, a steam exhaust passageway, a steam delivery passageway, and on at least one side thereof a longitudinal upstanding face disposed laterally beyond the adjacent side frame member to provide increased lateral space within said saddle, said face being adapted for attachment of a side cylinder casting; and a cylinder casting secured to said upstanding face.

16. In a locomotive, the combination of a cylinder saddle having at each of its sides an attaching face for a cylinder casting, the said faces converging downwardly; and two side frame members terminating at their front ends at the rear of the saddle, and each disposed inwardly of the adjacent side face of the saddle.

17. In a locomotive, the combination of a cylinder saddle having a middle cylinder, and side faces for the attachment of cylinder castings, the said faces converging down-

wardly; and two parallel side frame members terminating at their front ends at the rear of the saddle and each disposed inwardly of the adjacent side face of the saddle.

18. In a locomotive, the combination of a cylinder saddle having a middle cylinder, a valve chest for said cylinder, and side faces for the attachment of cylinder castings, the said faces converging downwardly; and two parallel side frame members terminating at their front ends at the rear of the saddle and each disposed inwardly of the adjacent side face of the saddle.

19. In a locomotive, the combination of a cylinder saddle having a middle cylinder, a valve chest for said cylinder, a steam exhaust passageway, a steam delivery passageway, and side faces for the attachment of cylinder castings, the said faces converging downwardly; and two parallel side frame members terminating at their front ends at the rear of the saddle and each disposed inwardly of the adjacent side face of the saddle.

20. An integral casting for locomotives comprising a cylinder saddle having a middle cylinder, a valve chest for said cylinder, a steam exhaust passageway, a steam delivery passageway, and side faces for the attachment of cylinder castings, the said side faces converging downwardly; two parallel side frame members terminating at their front ends at the rear of the saddle, each side frame member being disposed inwardly of the adjacent side face of the saddle; and a front frame member extending forwardly of the saddle.
